(57) **CLAIM**

The ornamental design for a paw shaped can holder, as shown and described.

DESCRIPTION

FIG. 1 is a front elevation view of a paw shaped can holder showing my new design;

FIG. 2 is a rear elevation view thereof;

FIG. 3 is a left side view thereof;

FIG. 4 is a right side view thereof;

FIG. 5 is a top plan view thereof; and,

FIG. 6 is a bottom plan view thereof.

The broken lines shown in the drawings represent portions of the paw shaped can holder that form no part of the claimed design.

1 Claim, 4 Drawing Sheets

FIG. 3

FIG. 4
